UNITED STATES PATENT OFFICE.

WILLIAM H. NELSON, OF WASHINGTON, DISTRICT OF COLUMBIA, ASSIGNOR
OF TWO-THIRDS TO CUTHBERT W. RIDLEY AND FREDERICK MERTENS,
OF WASHINGTON, DISTRICT OF COLUMBIA.

NUT-LOCK.

SPECIFICATION forming part of Letters Patent No. 716,085, dated December 16, 1902.

Application filed November 21, 1901. Serial No. 83,146. (No model.)

To all whom it may concern:

Be it known that I, WILLIAM H. NELSON, a citizen of the United States, residing at Washington, District of Columbia, have invented 5 certain new and useful Improvements in Nut-Locks, of which the following is a specification.

This invention relates to nut-locks, and has special reference to that type of locks designed 10 for securely fastening the nuts of a plurality of bolts.

The present invention relates to that class of such devices comprising a thin bar having a plurality of bendable tongues to be bent to 15 embrace the sides of the nuts and openings for the passage of the bolts.

The novelty in the present instance resides in the peculiar construction and adaptation of parts, all as more fully hereinafter described, shown in the drawings, and then particularly pointed out in the claim.

In the drawings, Figure 1 is a perspective view of a rail-joint fitted with the improved nut-lock constructed in accordance with the 25 present invention. Fig. 2 is a perspective view of the nut-lock, showing in dotted lines the nuts and illustrating the different ways in which the fastening-tongues may be employed. Fig. 3 is a plan view of the nut-lock 30 blank, illustrating the preferable construction thereof.

Like numerals of reference designate corresponding parts in the several figures of the drawings.

35 In the preferable construction, as shown in the drawings, the nut-lock essentially consists of a continuous locking-bar 1, having offset from one side thereof a plurality of individual lock-washers 2, each of which is an integral part of the bar 1 and is of a sufficient area to constitute a complete washer for the nut designed to work thereover. Each of the said lock-washers 2 is preferably provided with a plurality of laterally-projecting bendable fastening-tongues 3, which are of a sufficient length to bend up a material distance over or against a side of the nut to firmly brace the same against turning. In the construction illustrated it is found to be of advantage to employ a plurality of the laterally-

projecting fastening-tongues 3, inasmuch as while ordinarily one of such tongues is sufficient to constitute a lock for the nut, still in the event of such tongue becoming broken another may be brought into action, thus retaining the efficiency of the lock and greatly prolonging its durability. 55

The laterally-projecting bendable fastening-tongues 3 of the individual washers 2 may radiate from the body of the washer in directions best suited for the particular kind of work; but ordinarily there are a pair of diametrically opposite tongues 3, which, if desired, can be brought up against opposite sides of the nut by the means of claw-pincers or 60 like tools, as indicated in Fig. 2 of the drawings.

Each of the individual washers 2 is provided with a central bolt-opening 4, through which the bolt projects, and therefore permits of the nut-lock being readily slipped over the bolt ends before the nuts are secured into position upon the faces of the washers. It is therefore obvious that the lock as an 70 entirety may be quickly placed in position and the tongue or tongues 3 also quickly bent up against the sides of the nuts after being 75 screwed tight by any convenient form of tool. This is a great advantage in railway constructions, particularly where a ready and 80 quick application of a nut-lock is especially desirable.

In the application of the nut-lock to a rail-joint such as shown in the drawings the single locking-bar 1 is disposed next to the base 85 of the rail and lies wholly at one side of the plane of the bolts and nuts, thereby constituting not only a coupling between the several individual washers, but also a rigid brace which positively prevents any independent 90 movement of the individual washers. In effect all of the nuts with which the lock is associated may be said to be locked together by common means. The said advantageous results would attend the use of the nut-lock in 95 bridgework and other places.

From the foregoing it is thought that the construction and use of the herein-described lock will be readily apparent without further description. 100

Having thus described my invention, what I claim as new, and desire to secure by Letters Patent, is—

As an improved article of manufacture, the 5 nut-lock herein described consisting of a continuous locking-bar of thin metal having offset from one side thereof at the ends and intermediate thereof, independent like washers each integral with the bar and of sufficient 10 area to constitute a complete washer in itself, each of said washers formed with a plurality of lateral - projecting bendable fastening-tongues, each washer being provided with a centrally-disposed opening and the tongues 15 being of less width than the sides of the off-

set portion from which they extend, said tongues being in the plane of the bar with the outer end tongues projecting beyond the ends of the bar proper, the main longitudinal portion of the bar adapted to extend beneath 20 the nuts and the bendable tongues to be engaged over one or more of the other sides thereof, all substantially as herein shown and described.

In testimony whereof I affix my signature 25 in presence of two witnesses.

WILLIAM H. NELSON.
